UNITED STATES PATENT OFFICE

2,445,902

ENGINE DRIVE

Joseph D. Bell, San Francisco, Calif.

Application March 26, 1945, Serial No. 584,876

8 Claims. (Cl. 74—56)

1

The present invention relates to improvements in an engine drive, and has particularly reference to a cam drive such as has been described in my co-pending applications, Serial Number 518,466, filed January 15, 1944, now Patent 2,440,674, issued May 4, 1948, and Serial Number 566,765, filed December 5, 1944.

In the first application it was proposed to provide two concentric helical cam tracks interlocked for rotary movement in opposite directions, and a rectilinearly movable drive pin engaging over both cam tracks at their intersections for rotating the cam tracks on the power stroke and for being lifted by the cams on the return stroke. An additional cam track was provided to exert pull on the pin on the suction stroke of the engine.

In the second application it was proposed to provide two cam tracks for the suction stroke as well as for the drive stroke of an engine, and a specific arrangement was shown for solving certain structural problems, inasmuch as the pin was arranged to project over the cam tracks from the outside, which made it necessary for the outer cam at least, to extend through the entire thickness of the cylinder carrying the cam.

In the present invention it is proposed to provide a different structural arrangement for solving the problem outlined hereinabove.

The principal object of the present invention is to provide an engine drive of the character described which is more compact than that shown in the second application, and which allows the overall length of the entire structure to be reduced considerably.

It is further proposed to provide a structural arrangement in which certain parts revolve about the axis of rotation at a sufficient radial distance to produce a definite and appreciable fly-wheel effect, which makes it possible to dispense with the conventional fly-wheel and which tends to produce smooth operation and to reduce vibration.

A still further object of my invention is to combine the various features into a comparatively simple structure of rugged character, arranged to allow a number of drive pins, in the case illustrated four pins, to operate on the same cam tracks, whereby the four cylinders of the engine may be grouped around the axis of the tracks immediately above the cam track arrangement, so as to form a compact, powerful unit therewith.

Further objects and advantages of my invention will appear as the specification proceeds,

and the novel features of the same will be fully defined in the claims attached hereto.

The preferred form of my invention is illustrated in the accompanying drawing, forming part of this application, in which:

Figure 1 shows a side view of my engine drive with certain portions broken away;

Figure 2, a vertical central section through the same;

Figure 3, a sectional detail view taken along line 3—3 of Figure 2; and

Figure 4, a horizontal section taken along line 4—4 of Figure 2.

While I have shown only the preferred form of my invention, I wish to have it understood that various changes or modifications may be made within the scope of the claims hereto attached without departing from the spirit of the invention.

Referring to the drawing in detail, the main shaft 1 is mounted in two plates 2 held in spaced and parallel relation by any suitable means, as by the spacing rods 3 and nuts 4. The shaft has a cylinder 5 fixed thereto by means of a hub 6, and the cylinder is formed with opposing cam tracks 7 and 8 which preferably extend through the entire thickness of the cylinder walls. These two sections of the cylinder thus formed are secured upon the hub in any suitable manner, as by welding, or by means of screws, or by being made an integral part thereof.

The shaft has revolvably mounted thereon, underneath the cylinder 5, a hub 9, which carries a cap 10 surrounding the cylinder 5 and terminating, at its upper end, in a cam track 11 corresponding in shape substantially to the lower cam track 7 on the cylinder 5.

A sleeve 15 is secured to the cap 10 by means of brackets 16 so as to surround the upper portion of the cap and to be spaced from the same by a considerable distance. This sleeve is formed with an upper cam track 17 which corresponds in shape substantially to the upper cam track 8 of the cylinder 5.

The sleeve may also be formed with a lower cam track 18 facing the upper cam track 17 and corresponding in shape to the lower cam tracks 7 and 8 on the cylinder 5, respectively.

It will be noted that the sleeve 15 in this manner is mounted at a considerable radial distance from the axis of rotation, and that, given a certain weight, it has a definite fly-wheel effect.

The cap 10 and the cylinder 5 are interconnected for rotation in opposite directions by means of two ring gears 20 and 21, secured upon

the cap and the shaft 1, respectively, and meshing with pinion 22 revolvably supported in fixed frame members 23.

For driving the cylinder 5 and the cap 10 in opposite directions, I use, in the present instance, four pistons 24, which may form part of the conventional four-cycle internal combustion engine.

The four pistons 24 are grouped evenly about the axis of rotation of the main shaft, and centrally over the space between the cap 10 and the sleeve 15. The connecting rods 25 are preferably fixed to the piston and extend into the said space with freedom of rectilinear movement in response to piston movements. The rods are guided by means of fins 26 riding in channels 27 suspended from the upper plate 2, as at 28, and extending into the space between the cap 10 and the sleeve 15.

It should be noted that the guide channels 27 extend into these spaces only through a certain distance so as to clear the brackets 16.

The connecting rods are provided, at their lower ends, with drive pins 30 which latter again support rollers 31 for riding on the various cam tracks 7, 8, 11, 17 and 18.

The operation of my engine drive may be explained as follows:

Each cam track is shown in the form of a double wave, with two depressions and two crests. In the drawing a position is shown in which all the crests register and all the depressions register.

When the cylinder 5 and the cap 10 with its sleeve 15 rotate in opposite directions, it is obvious that the crests of the cams form a crotch into which the drive pins descend for deepening the crotch, and for driving the cap and the cylinder in opposite directions.

Assuming that the left-hand piston 24 is at the beginning of the power stroke, the drive pin will cause the cylinder 5 and the cap 10 to revolve in opposite directions until the end of the power stroke is reached. During this stroke the drive pin with its rollers will bear on the lower cam tracks 7, 11 and 18.

Upon continuation of the revolving movement, the same cam tracks will lift the piston 24 back to its original position on the exhaust stroke.

The third stroke is the intake stroke, and it is necessary for the drive pin to be pulled downward by the revolving cylinder 5 and the cap 10. During this stroke, the cams 17 and 8 become active, and bearing down on the rollers 30, pull the piston downward for sucking in a charge.

On the fourth, or compression stroke, the lower cam tracks 7, 11 and 18 again become active on the rollers for lifting the piston 24 back to its original position.

It will be noted that in this manner perfect balance is obtained, each drive pin having at least two cooperative cam tracks for lifting the same and for being driven thereby, and also two cooperative cam tracks for pulling the piston downward on the suction stroke.

The arrangement is very compact, allows of very close relationship between the different operating parts, while at the same time the outer sleeve 15 has a definite fly-wheel effect, which is augmented by the ring gears 20 and 21.

I claim:

1. In an engine drive, a shaft having a cylinder mounted thereon, two spaced cam tracks in the cylinder, a cap revolvable about one end of the cylinder and having a cam track thereon in cooperative relation to one of the cylinder tracks, a sleeve fixed to the cap so as to surround the same

in spaced relation thereto and having a cam track in cooperative relation to the other cylinder track, and a drive pin mounted for rectilinear motion between the cap and the sleeve and in driving relation with all of the tracks.

2. In an engine drive, a shaft having a cylinder mounted thereon, two spaced cam tracks in the cylinder, a cap revolvable about one end of the cylinder and having a cam track thereon in cooperative relation to one of the cylinder tracks, a sleeve fixed to the cap so as to surround the same in spaced relation thereto and having a cam track in cooperative relation to the other cylinder track, and a drive pin mounted for rectilinear motion between the cap and the sleeve and having rollers in driving relation with all of the tracks.

3. In an engine drive, a shaft having a cylinder mounted thereon, upper and lower cam tracks arranged on the cylinder in facing relation, a cap revolvable about the lower end of the cylinder and having a cam track thereon in cooperative relation to the lower cylinder track, a sleeve fixed to the cap so as to surround the same in spaced relation thereto and having a cam track in cooperative relation with the upper cylinder track, and a drive pin mounted for rectilinear motion between the cap and the sleeve and in driving relation with all of the tracks.

4. In an engine drive, a shaft having a cylinder mounted thereon, upper and lower cam tracks arranged on the cylinder in facing relation, a cap revolvable about the lower end of the cylinder and having a cam track thereon in cooperative relation to the lower cylinder track, a sleeve fixed to the cap so as to surround the same in spaced relation thereto and having a cam track in cooperative relation with the upper cylinder track, and a drive pin mounted for rectilinear motion between the cap and the sleeve and having rollers in driving relation with all of the tracks.

5. In an engine drive, a shaft having a cylinder mounted thereon, two spaced cam tracks in the cylinder, a cap revolvable about one end of the cylinder and having a cam track thereon in cooperative relation to one of the cylinder tracks, a sleeve fixed to the cap so as to surround the same in spaced relation thereto and having a cam track in cooperative relation to the other cylinder track, a drive pin mounted for rectilinear motion between the cap and the sleeve and in driving relation with all of the tracks, and means for interconnecting the cylinder and the cap for rotary motion in opposite directions.

6. In an engine drive, a shaft having a cylinder mounted thereon, two spaced cam tracks in the cylinder, a cap revolvable about one end of the cylinder and having a cam track thereon in cooperative relation to one of the cylinder tracks, a sleeve fixed to the cap so as to surround the same in spaced relation thereto and having a cam track in cooperative relation to the other cylinder track, a drive pin mounted for rectilinear motion between the cap and the sleeve and in driving relation with all of the tracks, and means for interconnecting the cylinder and the cap for rotary motion in opposite directions, the said means comprising ring gears mounted on the shaft and the cap and fixedly mounted pinions interposed between the same.

7. In an engine drive, a shaft having a cylinder mounted thereon, two spaced cam tracks in the cylinder, a cap revolvable about one end of the cylinder and having a cam track thereon in cooperative relation to one of the cylinder tracks,

a sleeve fixed to the cap so as to surround the same in spaced relation thereto and having a cam track in cooperative relation to the other cylinder track, a drive pin mounted for rectilinear motion between the cap and the sleeve and in driving relation with all of the tracks, and means for interconnecting the cylinder and the cap for rotary motion in opposite directions, the said means comprising ring gears mounted on the shaft and the cap and fixedly mounted pinions interposed between the same, with the sleeve and the ring gears cooperating to produce a fly-wheel effect.

8. In an engine drive, a shaft having a cylinder mounted thereon, two spaced cam tracks in the cylinder, a cap revolvable about one end of the cylinder and having a cam track thereon in cooperative relation to one of the cylinder tracks, a sleeve fixed to the cap so as to surround the same in spaced relation thereto and having a cam track in cooperative relation to the other

cylinder track, fixed guide members projecting into the space between the cap and the sleeve and a drive pin mounted for rectilinear motion in the guide members and in driving relation with all of the tracks.
